UNITED STATES PATENT OFFICE.

EARL G. WATROUS, OF CHICAGO, ILLINOIS.

CLOSET.

Application filed August 8, 1918. Serial No. 243,989.

To all whom it may concern:

Be it known that I, EARL G. WATROUS, a citizen of the United States, residing at Chicago, in the county of Cook and State of Illinois, have invented certain new and useful Improvements in Closets, of which the following is a specification.

My invention relates to closets, and in some features more particularly to closets of the siphonic type. Its general object is to provide improved structure of the bowl and its support to afford simple, compact, and effective organization, and to enable the bowl to be mounted flush against a wall and out of contact with the floor. One feature of my invention pertains to the mounting of the bowl upon the upturned end of a soil pipe fitting extending into the wall. Another feature relates to the bowl construction, making it suitable to be installed flush against the wall and upon such a support as the stated soil pipe fitting. A further feature of my invention attains advantages of efficient siphonic action in the combination of bowl and soil pipe fitting, and also desirable economy of space. Other features of my invention, which consists in the construction, arrangement and combination of parts, hereinafter set forth in the claims will become apparent to those skilled in the art from the following description taken in conjunction with the accompanying drawings:—

In the drawings Fig. 1 is a longitudinal vertical section through a closet; Fig. 2 a rear elevation with parts in section taken on line 2—2 of Fig. 1; Fig. 3 a transverse vertical section on line 3—3 of Fig. 1; and Figs. 4, 5 and 6 are respectively plan, side-elevation and front elevation of a piping and support fitting.

The closet support particularly illustrated is intended to be united with and carried by a fixed soil pipe stud that will be located in the wall space, W representing a wall surface of any construction formed with an opening toward or into which the stud S extends. For connection with the threaded ends of such stud I provide a special pipe fitting 10 and a bowl unit 11 especially constructed for cooperation therewith. The fitting 10 in the particular construction shown comprises a threaded vertical head 12 as a preferred means of making rigid connec-

tion to the fixed pipe stud S, and it has its 55 opposite end upturned to present a horizontal orifice 13 around which the bowl unit may rest. Between its ends the passage through this fitting is down bent or dipped to form a well or trap 14 in which there will 60 normally reside a water body 15 that does not close an air passage through the fitting. Specifically I prefer that the bottom surface of the fitting shall curve downwardly from the head and then upwardly to the orifice 13, and that adjacent the head the fitting shall taper in cross section downwardly and forwardly as at 17 so that the cross section of the fitting through the well 14 may be smaller than that of pipe stud S. Surrounding the horizontal orifice 13 and slightly below its level the fitting is flanged as at 18, side ears 19 to receive fastening bolts 20 springing laterally from the flange and a stud 20 threaded to receive an adjusting 75 screw, and suitably ribbed for strength, projecting forwardly beyond the upturned end of the pipe at a level somewhat lower than the ears. A packing ring 21 surrounds the orifice 13 and makes tight joint with the 80 bowl unit seated thereon.

The earthenware bowl, in the particular form shown, is intended for support flush against the wall and out of contact with the floor. Its sides and top wall spring from a 85 thick abutting flange or vertical base 23 and sweep forward far enough to leave between the bowl opening 24 and the wall W, the necessary room for the seal passage 25 and the downtake passage 26. Preferably the 90 rear wall 27, of the bowl proper, dam wall 28, and rear wall 29 of the down-take sweep forwardly and downwardly, the bottom opening of the downtake registering, of course, with the orifice of the fitting 10. 95 The supporting bottom of the bowl unit is the solid flat surface 30 fitting on the packing ring 21, a flat abutment 31 being provided to receive the thrust of adjusting screw 32 extending through the stud 20, to 100 level the bowl structure and give additional support. The side walls of the bowl unit are formed to provide horizontal shoulders 34 apertured to receive screws 35 to engage the threaded ears 19 of the pipe fitting 10 105 as the primary fastening of the assembled parts. The side walls of the bowl unit are preferably carried down as wings 36 below.

the level of the pipe fitting 10, an opening 37 being left at the bottom to give access to the screw 32 and pipe coupling 10, the construction thus providing in substance a forwardly and horizontally extending chamber 38 open at the rear of the bowl unit, in which the pipe fitting that affords support to said unit is housed and effectively concealed. A water flow connection stub 40 may be anchored in the upper rear portion of the bowl unit below the top wall to connect through a passage with the flushing ring, 41, and it will be apparent that where the wall structure W is such as to make it practicable this 15 stub might be used as an auxiliary means to anchorage, as by arrangement of a plate 42 to bear against the wall and be held by the union 44 screwed on the stub. This is not needful, however, as the leveling action of 20 screw 20 may be depended on to hold the closet base 23 flush against the wall.

It will be apparent that my invention gives desirable economy in space requirement for closet installation and is advantageous in lending itself to artistic design and in affording a sanitary separation of the entire bowl unit from the floor. The pipe fitting 10 constitutes one very advantageous means for affording support to the bowl 25 unit from a fixed and strong soil pipe and the combination of bowl and pipe connections, including the characteristic trap-form of the pipe connection 10, gives a very effective siphonic action with a minimum space requirement. The water body normally resident in the well or trap 14, and the effective attenuation of the free pipe space above such water due to the dipping or down bending of the pipe unit 10, enables the 30 prompt formation of a complete seal as soon as flushing starts, and so causes the siphonic action to start quickly and enables the closet to work effectively under minimum water supply. Such closet will work very effectively from a low tank of small capacity. Further it will be observed that the siphon legs 25 and 26 and the pipe-fitting 10, clear 35 to the soil pipe S, are all free from obstructions that would tend to cause lodgment or clogging of solid matter. And also it will be noted that the separation of the well 14 from the bowl and its incorporation in a pipe fitting gives highly desirable simplicity in the bowl-unit and manufacturing economy.

While I have herein described only a single practical embodiment of my invention for purposes of disclosure, it will be understood by those skilled in the art that 40 my invention in its broader aspects is not limited to the details shown, but may be embodied in different specific forms within the spirit of my invention and scope of the appended claims.

What I claim is:

1. In a closet construction of the character described, wherein the closet is mounted against the wall and free from the floor, the combination of a rigidly supported horizontally extending soil pipe element, having a flanged horizontal front orifice, a bowl unit having a vertical base for wall contact, and a horizontally extending supporting surface to receive support from a pipe flange, means for securing said bowl unit to said pipe flange, and an adjusting screw carried by said pipe unit in front of its said orifice bearing against the bowl unit to adjust the level of the latter.

2. In a closet of the character described, the combination of a bowl unit having a bowl proper, a seal passage upwardly extending in rear thereof and a downtake in rear of said seal passage, and a wall-contacting vertical base at the rear of the unit, a soil pipe fitting having its forward end upturned and registering with said downtake, said pipe fitting supporting said bowl unit, and means fastening said bowl unit to said pipe fitting.

3. In a closet of the character described, the combination of a bowl unit having a bowl proper, a seal passage upwardly extending in rear thereof and a downtake in rear of said seal passage, and a wall-contacting vertical base at the rear of the unit, and a horizontally extending soil pipe element having an upturned front end registering with said downtake and having a well between its ends, said soil pipe element supporting said bowl unit.

4. In a closet of the character described, the combination of a bowl unit having a bowl proper, seal passage in the rear thereof, and rear downtake and having a vertical base and wall contact, said unit having also a horizontally extending chamber rearwardly open and passing beneath the bottom orifice of the downtake and bottom wall of the seal passage, there being an opening to said chamber at the bottom thereof, a soil pipe fitting forwardly extending into said chamber having its forward end upturned and flanged for register with the downtake and support of the bowl unit, means for connecting said bowl unit to the pipe fitting, and an adjustable leveling device carried by said pipe fitting and bearing against upper wall of the bowl unit passage, and accessible to the bottom opening of said passage.

5. The combination with a soil pipe stub horizontally extending above floor level and a bowl unit having a vertical base for wall contact, a bowl proper and seal and downtake passages in rear thereof, of a fitting secured to said soil pipe stub, extending for

wardly below the bowl and upturned to register with the downtake opening and supporting the bowl and means accessible from the exterior of the structure fastening said bowl to said fitting.

6. A fitting for the purpose described, comprising a horizontally extending pipe

element dipped between its ends, having its front end upturned to present a horizontal orifice and flanged about said orifice, said 10 forward end of the fitting provided with fastening receiving apertures and a forwardly extending stud 20.

EARL G. WATROUS.
